UNITED STATES PATENT OFFICE

WILLIAM HENRY NORRABLE, OF LEEDS, ENGLAND

POLISH AND LIKE TIN

Application filed January 26, 1929, Serial No. 335,358, and in Great Britain February 6, 1928.

This invention relates to polish and like tins of the type provided on the body thereof with a pivoted lever adapted to be actuated in a plane at right angles to the side of the 5 tin so as to cause the lid to be lifted and thereby facilitate its removal.

In tins fitted with lid-raising mechanism of this type, as hitherto proposed, one end of the lever is pivotally connected to that part 10 or rim of the tin which is normally covered by the depending flange of the lid, said end of the lever passing between the rim of the tin and the lid flange and the other end of the lever depending beside the body of the 15 tin. This arrangement necessitates upward actuation of the free end of the lever in a plane at right angles to the tin in order to raise the lid, and also entails recessing or 20 grooving of the rim of the tin to permit of the passage of the lever between it and the lid flange and to allow of its pivotal connection with said rim.

Now the object of the present invention is to provide lid-raising mechanism of the type 25 specified which will not entail recessing or grooving of the rim of the tin body and thereby prevent leakage, and which can be operated with one hand when the tin is lying flat on a table or the like.

According to the invention, the lid raising 30 lever is pivotally mounted on the side of the tin at a position outside the lid flange and adapted to be depressed outwardly from and in a plane at right angles to the side of the 35 tin to raise the lid.

In order that the invention may be clearly understood and readily carried into effect, the same will now be more fully described with reference to the accompanying drawings; 40 wherein:—

Figure 1 is a part front elevation of a lidded polish or like tin having one form of the invention applied thereto.

Figure 2 is a part sectional side elevation 45 taken on the line A. B. of Figure 1.

Figure 3 is a part side elevation of the tin shown in Figure 1 but illustrating the lid in a raised position.

Figure 4 is a part sectional side elevation 50 of a lidded polish or like tin having a modi-

fied form of the invention applied thereto.

Figure 5 is a part side elevation of the tin shown in Figure 4 but with the lid in a raised position.

Referring to Figures 1, 2 and 3 of the drawings, the lever 1 is of double-ended right angular form, the shorter arm engaging the edge of the flange of the lid 2 and the other arm being adapted to serve as a manipulating end. The right-angular lever 1, which in the embodiment illustrated is made of sheet metal, is provided with side projections 3 adapted to afford side trunnions or pivots for the pivotal mounting of the lever 1 within a sheet metal fitting or bracket 4 in the form of a U-shaped housing in plan, such housing or bracket 4 being welded or otherwise secured to the side of the tin body 5. The side trunnions or pivots 3 of the lever 1 engage appropriately positioned bearing holes 6 in the side walls or limbs of the U-shaped housing 4, and in this connection the bearing holes 6 are of such a size as to permit of a certain amount of play of the trunnions 3 within them, while the extremities of the limbs of the U-shaped housing or bracket 4 are provided with flanges 7 whose upper ends afford auxiliary pivotal supports for the lever 1 when the latter is turned outwardly (see Figure 3). 80

To ensure of a better engagement with the underside or edge of the flange of the lid 2, the end of the short arm of the lever 1 may be pointed or bevelled, and for this purpose also the edge of the flange of the lid 2, may, as shown, be turned outwardly or rolled upon itself. 85

The upper end of the lever 1 normally lies against the flange of the lid 2, as shown at Figures 1 and 2, and the arrangement is such that, when the lever 1 is turned or actuated in a plane at right-angles to the side of the tin 5, the lid is raised, as shown at Figure 3 so as to facilitate removal thereof whilst the lever 1 is automatically returned 90 to its normal position, ready for the next opening, by the re-application of the lid 2. 95

Instead of making the rightangular lever of sheet metal, it may be made of solid metal with integral side projections or trunnions, 100

or in lieu of such trunnions the lever may be bored through at the angle to take a pivot pin passed through it and the bearing holds in the side walls of the bracket or housing.

5 It will be seen that the lever 1 in its normal position, as shown in Figure 2, moves about a floating fulcrum formed by the enlarged openings 6, which receives the trunnions or lugs 3, so that as the latter moves in the 10 openings, and the lever 1 assumes the position as shown in Figure 3, the fulcrum is transferred to the inwardly opposed flanges 7. By reason of this novel arrangement of parts, the lever 1 will exert a vertical pull 15 on the edge of the lid 2 without effecting any outward or lateral drag thereon. Moreover, due to the transfer of the fulcrum from the openings 6 to the flanges 7, the lifting action is continued until the lower edge of the 20 lid flange reaches the top of the rim of the body 5, and thus allows a greater depth of lift to be obtained.

Referring now to the embodiment shown in Figures 4 and 5 of the drawings, a sheet 25 metal bracket or U-shaped housing 4 is riveted or otherwise secured to the side of the tin body 5 at its lower portion, and a straight sheet metal lever 1 is pivotally mounted within said U-shaped housing 4 by means of side 30 trunnions or pivots 3 engaging bearing holes 6 in the side or limbs of said housing 4. A strip of tape or other material 8 secured to the inside of the tin body 5 and passing between the depending flange of the lid 2 and 35 the rim portion of the tin body 5 to the outside thereof is secured to the lever 1 at a point intermediate its pivotal connection and its free end, the arrangement being such that, upon actuation of the lever 1 in a plane at 40 right-angles to the side of the tin, the pull of the lever 1 straightens out the tape 8 and thereby raises the lid 2 as shown at Figure 5. Re-application of the lid 2 causes the lever 1 to re-assume its normal position against 45 the flange of the lid 2. The tape 8 may not be secured to the tin body 5.

I am aware that it has before been proposed to employ a strip of flexible material passed between the lid flange and the rim of the 50 tin for opening purposes by exerting a pull on the outer end of said strip.

I claim:—

1. In combination with a container having a removable lid, of means for raising the lid 55 comprising a bracket having parallel sides and inwardly extending opposed flanges secured to the container, said parallel sides having aligned openings, a lever having angularly disposed portions and laterally extending lugs, said lugs arranged to loosely fit within said openings to provide a floating fulcrum for the lever, one portion of the lever normally engaging the lower edge of said lid whereby upon the actuation of the 60 other portion, the fulcrum is transferred 65

from the floating fulcrum to the opposed flanges of said bracket and the lid removed from the container.

2. In combination with a container having a removable lid, of means for raising the lid 70 comprising a bracket having parallel sides and inwardly extending opposed flanges secured to the outside of the container, said parallel sides having aligned openings, a lever having angularly disposed portions and laterally extending lugs, said lugs arranged to loosely fit within said opening to provide a floating fulcrum for the lever, the end of 75 one portion of the lever normally engaging the lower edge of said lid, said opposed flanges acting as an auxiliary fulcrum for the other portion of the lever when the latter is moved outwardly relative to the container.

3. A lid remover of the class described comprising a support, a lever having a lid engaging portion and a handle portion, said portions being angularly disposed relative to each other, means providing a floating fulcrum connection between said lever and said support, and means on said support providing an auxiliary fulcrum for said lever. 80

4. A lid remover of the class described comprising a support, a lever having a lid engaging portion and a handle portion, said portions being angularly disposed relative to each other, means providing a floating fulcrum connection between said lever and said support at the juncture of said portions, and means on said support providing an auxiliary fulcrum for said lever when said handle 90 portion is moved outwardly relative to the support.

WILLIAM HENRY NORNABLE.
